UNITED STATES PATENT OFFICE.

WESLEY G. NICHOLS, OF CHICAGO, ILLINOIS, ASSIGNOR TO AMERICAN MANGANESE STEEL COMPANY, OF CHICAGO, ILLINOIS, A CORPORATION OF MAINE.

INSERTED-CENTER RAILWAY CROSSING.

1,427,122.

Specification of Letters Patent. Patented Aug. 29, 1922.

Application filed January 25, 1922. Serial No. 531,527.

To all whom it may concern:

Be it known that I, WESLEY G. NICHOLS, a citizen of the United States, residing at Chicago, in the county of Cook and State of Illinois, have invented certain new and useful Improvements in Inserted-Center Railway Crossings, of which the following is a specification.

This invention relates to railway crossings in which the treads and the guards of two intersecting rails, at the crossing point, are formed of a single piece inserted in the crossing structure, and is intended primarily for use in inserted centers formed of manganese steel.

The object of the invention is to support the insert in a manner to better enable it to withstand the shocks incurred in service, and also to better insure it against unintentional release of its securing means.

The invention consists in supporting the insert through means which leave it in substantially a floating status, so that a considerable portion of shock, in excess of that required for overcoming the inertia of the piece, will be absorbed by a slight yielding of the insert; the means for floating the insert being also utilized to maintain the securing means against displacement which would release the insert; and a shock absorbing support, preferably in the form of a laminated sheet metal cushion, being provided in such relation to the insert as to limit the yielding movement through a cushioning resistance.

In order that the invention may be fully understood, the preferred embodiment thereof will be described in connection with the accompanying drawing, in which—

Figure 1 is a plan view of a crossing having an insert constructed in accordance with the present invention.

Figure 2 is a section on the line 2^x—2^x of Figure 1.

Figure 3 is a bottom plan view of the insert on a reduced scale; and

Figure 4 is a section on the line 4^x—4^x of Figure 1.

1 represents a frame designed to unite with four rails of a crossing intersecting at an angle of 90°, but it may obviously be designed for other angles of crossing.

Frame 1 is provided with a central recess 2 that receives an insert 3 with sufficient freedom to permit said insert to be intro-

duced and removed at will, and also to move vertically within the recess while in service. Insert 3 is constructed with marginal sustaining walls 4, shown in section in Fig. 2 and in bottom plan in Figure 3, which largely sustain loads imposed upon the insert, and in addition thereto it may have diagonal cross walls 5 beneath its flange grooves 6, and therefore in such relation to its treads 7 and guards 8 as to strengthen the latter against the load of passing wheels.

The side walls 4 and diagonal walls 5 (when the latter are employed) preferably terminate below in the same horizontal plane, so that they all rest upon a laminated sheet metal cushion 9 confined in the recess 2, and of such thickness that they will receive the vertical load imposed upon the insert 3 with very little lost motion of said insert.

Protruding laterally from the insert 3, and preferably in positions intermediate of flange grooves 6, are supporting ears 10 in position to be sustained by springs 11 resting upon lugs or other suitable faces provided on the frame 1 and adapted to present the insert 3 normally in a floating or approximately floating status. It is not necessary that springs 11 be of sufficient strength to sustain any material part of the load imposed upon the insert; they may be designed merely to overcome the normal weight of the insert and hold it up so as to keep under tension, or at least sustained against material depression, bolts 13 which secure the insert against vertical displacement. Bolts 13 are preferably provided with T-heads 14 adapted to pass through slots 15 in the lugs 12, and are confined in seats 16 on the underside of the lugs when the heads are turned 90° to the seats 16; and on their upper ends said bolts are provided with securing nuts 17 which may be adjusted to depress the insert 3 in opposition to springs 11 until the insert assumes exactly the desired level. Adjustment of nuts 17 may be retained in any desired way, as, for instance, by pouring spelter or other filling material in the undercut cavities 18 surrounding said nuts. In this construction, the springs 11 become the means for keeping the bolts under tension and preventing displacement of the heads 14 from their seats 16, in addition to the previously described function of float-

ing the insert.

The insert is preferably polygonal in form (in the selected embodiment, square), and the flange grooves, treads, and guards run from corner to corner, thereby presenting the edges 19 of the insert at an angle to the line of travel, and causing the bearing line of the wheel to bridge the space at 19 instead of dropping into the same, and the securing and supporting ears project from 10 sides of the polygon, or symmetrically on opposite sides of each wheel-receiving point so that the wheel impact is divided between them.

I do not herein claim the feature of floating the insert by means of the laminated sheet metal cushion 9, as this constitutes the subject-matter of claims in my application, Serial No. 499,762, of earlier filing date.

I claim:

- 20 1. In a railway crossing, a frame, a crossing insert mounted in said frame, cushioning means adapted to absorb loads imposed on said insert, and means independent of said cushioning means for floating said insert.
- 25 2. In a railway crossing, a frame, an insert mounted in said frame and movable vertically, relatively thereto, means for limiting vertical depression of the insert in the frame, and independent means for floating the insert in said frame.
- 30 3. In a railway crossing, a frame, an insert mounted in said frame, bolts for retaining said insert, and resilient means adapted to sustain the normal load of the insert, tending to displace it against the retention of its bolts.

4. In a railway crossing, a frame, an insert mounted in said frame, a resilient support for said insert, securing means for resisting removal of said insert, and additional resilient means acting upon said insert in opposition to its securing means.

5. In a railway crossing, a frame, an insert mounted in said frame and having downwardly extending supporting walls, resilient means located under said supporting walls, ears projecting from said insert beyond said supporting walls, means engaging said ears to secure the insert against vertical displacement, and resilient means acting upwardly against said ears in opposition to said securing means.

6. In a railway crossing, a frame, an insert in said frame comprising a horizontal upper wall having intersecting trackage extending across it, and intersecting walls depending vertically therefrom beneath said trackage, and adapted to enter into vertical bearing to support said horizontal wall.

7. An insert for railway crossings, comprising a horizontal upper wall having intersecting trackage across it, marginal walls depending vertically from about the perimeter of said horizontal wall, and intersecting walls bridging the space between said marginal walls depending vertically beneath said trackage and adapted to enter into bearing upon the same surface with said marginal walls.

Signed at Chicago, Illinois, this 30th day of December, 1921.

W. G. NICHOLS.
